UNITED STATES PATENT OFFICE.

FRITZ MÜLLER, OF BERNE, SWITZERLAND, ASSIGNOR OF ONE-HALF TO ALOIS LEUTENEGGER, OF OLLEN, SWITZERLAND.

DRAW-BAR BALANCE FOR VEHICLES.

1,333,932.

Specification of Letters Patent. Patented Mar. 16, 1920.

Application filed September 10, 1918. Serial No. 253,466.

To all whom it may concern:

Be it known that I, FRITZ MÜLLER, a citizen of the Swiss Confederation, and residing at Berne, Switzerland, have invented 5 certain new and useful Improved Draw-Bar Balances for Vehicles, of which the following is a specification.

My invention relates to a novel draw bar balances for vehicles. It possesses two 10 angle-levers, which on their one end are held together and in the direction of the shaft are removably guided. These angle-levers are joined on their elbows to draw-bars which cross each other and are fastened on 15 the other end to the shaft.

This permits a nearly symmetrical movement of the levers. In case of an unequal pull of the horses, the weaker one will not be drawn back, as it is the case with ordinary draw-bar balances in use, but the new 20 device will in an elastic manner permit the weaker horse to hold step with the stronger horse.

This contributes materially to an easy 25 start of the vehicle as the horses are bound to work better together, which avoids an overworking of the horses as well as a loss of energy.

The invention consists of novel features 30 and parts and combinations of the same, which will be more fully described herein-after and then pointed out in the claims.

A practical embodiment of the invention is represented in the accompanying drawing, 35 in which similar characters of reference indicate corresponding parts in all the views.

Figure 1 is a top view of the drawbar-balance, 40 Fig. 2 a section taken at the line II—II on Fig. 1; and Fig. 3 a sectional view on line III—III of Fig. 1.

The two draw-bars 1 are connected by means of hooks and rings to the free ends 45 of the angle-levers 2, whose other ends are connected together by means of a bolt 3. The lower end of this bolt is engaged in a guide slot 4 on the shaft 10 of a vehicle not shown and can move to and fro in the longitudinal axis of the shaft.

A pair of crossed tension rods 6 are attached on the elbows of the angle-levers 2 and likewise a spiral spring 12 which draws

together the two elbows of the angle levers. The other ends of the tension rods are connected by means of bolts 7 to the ends of a lever 8, whose turning bolt 9 is fastened on the shaft 10.

The pull on the draw bars 1 in the direction of the arrows is transferred on the 60 shaft by means of the system of joints of the parts 2, 6 and 8.

The angle-levers 2 turn around fulerums 5, which on account of the disposition of the tension rods 6, in opposition to the spiral 65 spring force 12, move outward and permit the bolt 3 to slide backward in the guide slot 4.

The ends of the angle-levers 2 which hold the draw-bars move forward for the same 70 distance, in case the tractive effort on both ends is practically the same. In the other event, the distance will not be the same, because the crossing tension rods 6 and the lever 8 will permit the turning point 5 on the 75 elbow of the one angle lever 2, on which the greater pull is exerted, to make a greater sideward movement. This allows a certain balance between both tractive efforts, through which an equal starting pull of the 80 two horses is gained. The forward rocking movement of the angle levers 2 is limited by noses 11 provided on their joined ends.

What I claim is:

1. A draw-bar balance for vehicles comprising in combination with the shaft of the vehicle two angle-levers forming drawbars and joined at their one ends, means for guiding these ends in the longitudinal axis of the shaft, and mutually crossing tension 90 rods pivotally connected to the elbows of said levers and pivoted to the shaft with their other ends.

2. A draw-bar balance as specified in claim 1, in which a two-armed lever is provided fulcrumed on the shaft, the free ends of the tension rods being connected to the arms of said lever.

3. A draw-bar balance as specified in claim 1, in which the two angle levers are joined by a bolt engaging in a guide slot provided on the shaft in its longitudinal axis.

4. A draw-bar balance as specified in claim 1, in which the joined ends of the 105 angle-levers are formed with noses for lim-

iting the forward rocking movement of the levers.

5. In a draw-bar balance as specified in claim 1, a spring connecting the angle levers at their elbows resisting the forward rocking movement of the free ends of said levers.

In testimony whereof, I affix my signature in the presence of two witnesses.

FRITZ MÜLLER.
